UNITED STATES PATENT OFFICE.

WILLIAM L. EVERIT, OF NEW HAVEN, CONNECTICUT.

CAR-FLOOR.

SPECIFICATION forming part of Letters Patent No. 397,420, dated February 5, 1889.

Application filed November 26, 1888. Serial No. 291,869. (No model.)

To all whom it may concern:

Be it known that I, WILLIAM L. EVERIT, of New Haven, in the county of New Haven and State of Connecticut, have invented a new 5 Improvement in Car-Floors; and I do hereby declare the following, when taken in connection with accompanying drawings and the letters of reference marked thereon, to be a full, clear, and exact description of the same, and 10 which said drawings constitute part of this specification, and represent, in—

Figure 1, a plan view of the floor of a street-car embodying the invention; Fig. 2, a longitudinal section cutting through one of the 15 channels at the side looking outward; Fig. 3, a longitudinal central section of a portion of the floor cutting through the opening over the truck; Fig. 4, a transverse central section through the same opening; Fig. 5, a transverse 20 section cutting through the central traps, showing the channels; Fig. 6, a modification.

This invention relates to an improvement in the construction of street-car floors.

Street-car floors have been constructed with 25 longitudinal parallel ribs arranged theron, the ribs terminating near each end, but leaving a space between the ends of the ribs and the ends of the car, so that the channels between the ribs would open freely at the ends 30 as a convenience for cleaning the floor. Such a floor is described in a patent granted to me September 3, 1878, No. 207,726. The longitudinal ribs are in many cases objectionable, because the grooves and ribs are in the direction of the line of step, and consequently make 35 an uneven and often uncomfortable surface for the feet and uncomfortable to walk or stand upon.

The object of my invention is to retain the 40 advantage of stationary ribs on the floor, but yet avoid the difficulties mentioned; and the invention consists in series of stationary parallel ribs arranged transversely across the floor, but terminating near each side, so as to 45 leave a longitudinal open space at the ends of the ribs, which extends to the ends of the car as a convenience in sweeping or cleaning the floor, and in details of construction, as more fully hereinafter described.

50 A represents the floor of the car. On this

floor transverse parallel ribs *a* are arranged a short distance from each other and so as to leave grooves *b* between the ribs running transversely across the floor. These ribs are shorter than the exposed surface of the floor. 55 That exposed surface is here represented as limited by longitudinal ribs *b'*, (see Fig. 1,) so that a longitudinal open space, *d*, extends along the ends of the ribs to the respective ends of the car, and at the ends these longitudinal spaces *d* should open onto the floor of the car, so that as the car is swept transversely the dirt will pass into the longitudinal spaces and there may be swept longitudinally to the end of the car and out onto the floor. 65

I prefer to make the longitudinal spaces *d* at the ends of the ribs in the form of a channel, as seen in Figs. 2 and 5, the channel deepening from the ends toward the center, and at the center a trap, *e*, is arranged which may be 70 readily removed, so that any drip from the floor will naturally run to the channels and thence be led away through the bottom of the car. This trap may also afford a convenient means for discharging the sweepings. The 75 recessed channels, however, may be omitted, as seen in Fig. 6, the level floor being all sufficient for sweeping purposes.

In cars which are driven by electricity an opening through the car-floor onto the trucks 80 is necessary. To provide such an opening, I arrange a trap, *B*, in the floor, which is simply a hole in the floor of the required size, with a removable cover adapted to set in and close the opening, the cover being provided with 85 ribs corresponding to the ribs of the floor, as shown, and this trap is packed around its edge, as seen at *f*, Figs. 3 and 4.

Under this construction the floor is provided with ribs, which obviate the use of removable 90 mats, and because the ribs and grooves are transversely across the floor they do not interfere with the comfortable walking or standing in the car.

From the foregoing it will be understood 95 that I do not claim, broadly, a car-floor provided with stationary ribs adapted to leave corresponding grooves between them; but

What I do claim is—

1. A car-floor having stationary ribs ar- 100

ranged transversely thereon and distant from each other, so as to form grooves on the floor-level between the said ribs, the said ribs terminating short of the width of the floor of the car and so as to leave clear longitudinal spaces at the ends of the ribs, substantially as described.

2. A car - floor provided with stationary transverse ribs forming transverse grooves on the floor, the said ribs stopping short of the full width of the floor and so as to leave a clear longitudinal space, d , at the ends of the ribs, the said longitudinal space recessed to form a channel inclining from each end of the car downward toward the center, combined with a trap at the center through which said channels may discharge, substantially as and for the purpose described.

3. In a car-floor having ribs arranged transversely across it and so as to form transverse grooves between said ribs, the said ribs stopping short of the full width of the floor, so as to leave a clear longitudinal space at each side, the floor constructed with an opening through to the trucks beneath, a cover, B, provided for said opening, the said cover having ribs on its upper surface corresponding to the ribs of the floor, and the said opening provided with a packing, substantially as described.

WILLIAM L. EVERIT.
